(57) **CLAIM**

We claim the ornamental design for a dispensing device, as substantially shown and described.

DESCRIPTION

FIG. 1 is a perspective view of a dispensing device, in accordance with the present invention;

FIG. 2 is a front view thereof;

FIG. 3 is a side view thereof;

FIG. 4 is a side view thereof;

FIG. 5 is a back view thereof;

FIG. 6 is a top view thereof; and,

FIG. 7 is a bottom view thereof.

The broken lines in the figures illustrate the portions of the design that form no part of the claimed invention.
